UNITED STATES PATENT OFFICE.

WILLIAM VICKERY, OF LONDON, ENGLAND.

FEED MECHANISM FOR PRINTING OR LIKE MACHINES.

SPECIFICATION forming part of Letters Patent No. 752,488, dated February 16, 1904.

Application filed November 23, 1901. Serial No. 83,442. (No model.)

To all whom it may concern:

Be it known that I, WILLIAM VICKERY, a subject of the King of Great Britain, residing at 13 St. Ann's Villas, Notting Hill, London, England, have invented certain new and useful Improvements in or Connected with Feed Mechanism for Printing or Like Machines, of which the following is a specification.

The object of this invention is improvements in or connected with feed mechanism for printing or like machines, whereby a pile of paper on a raising table is presented at the proper height to a roller or rollers or other device on the end of a lever or levers situate on a shaft for the roller to grip the paper and convey the top sheet of the pile onto and over a tilting table, this having been at the moment lowered, and so soon as the top sheet of paper has been drawn onto it by the roller is lifted to raise or free the top sheet from the pile. The paper is then passed to a set of rollers by which it is gripped and carried away over the tilting board down an inclined board having driver-rollers to the stops, each sheet in succession being gripped by a device to insure perfect side lay, after which fingers press upon the sheet of paper and hold it firmly in the true position, while the cylinder-grippers have taken hold of the sheet and the paper removed, when the fingers lift and allow a fresh sheet of paper to pass into place for a fresh operation.

My invention will be understood from the following description, aided by the accompanying drawings, in which—

Figure 1 is an elevation of sufficient of one side of a printing-machine with my invention applied. Fig. 2 is a similar view, but from the other side of the machine. Fig. 3 is a plan. Fig. 4 is a view, on an enlarged scale, showing the gear-wheels and the arm for starting or stopping the same. Fig. 5 is a section of the starting and stopping appliance as fixed on shaft. Fig. 6 is a view showing the cam and lever for working the fingers. Fig. 7 is a plan, on an enlarged scale, of part of my attachment for actuating the rocking table. Fig. 8 is a plan view of the slide, the weighted lever carried thereby, the fingers,

and the mechanism for actuating the same. Fig. 9 is a sectional elevation of the front or entering end of the machine. Figs. 10 and 11 are detail views, in side and front elevation, respectively, of the knuckle-jointed lever. Fig. 12 is a similar view of a cam and a power-transmitting rod. Figs. 13 and 14 are opposite side elevations of the parts shown in Fig. 8. Fig. 15 is an elevation of the said weighted lever and stops for actuating the latter.

For the purpose of my invention I place the raising table *a* at an angle and support same by uprights *b*, these being slidably connected to posts or standards *c*, forming the framework of the feeding mechanism. These uprights *b* are in connection by chain *d* or suitable gearing with an auxiliary shaft *e*, carrying a many-toothed ratchet or other wheel *f*, operated by a pawl *g* on the end of a rod *h*, which is in connection by an arm *i* with a shaft *j*, carrying fingers *k*, which fingers *k* by their adjustable nose-pieces *l* have a pressure on the pile of paper and insure the mechanism bringing the table up to the proper height for perfect feed.

Fixed on the shaft *j* is an arm *m*, the free end of which is supported by a spring *n*, encircling a rod *p*, the spring *n* supporting the arm *m* for adjusting the pressure of the fingers *k* on the pile of paper and relieving the parts of the strain and weight of the rod *h* and arm *i*.

The arm *i*, and consequently the slotted rod *h*, ratchet *f*, and raising table *a*, are actuated by a cam *q* on the main shaft *r*, also carrying a spring-controlled knuckle-jointed arm *s* or arms constructed as at Figs. 10 and 11, said arm carrying rollers *t*, which as they come round press upon the top of the pile *u* and draw the top sheet off onto a tilting table *v* for being passed through the feed mechanism.

The tilting table *v* is pivoted to the framework *c* of the mechanism at *w*, and is so situate that when at its lowest position it is just below the top of the pile of paper *u*, as at Fig. 1, and such tilting table *v* is connected with a rod *x*, having a roller *y*, acted upon by the cam *z*, for raising by the cam action from the main shaft at the moment the top sheet of the

pile has been drawn over it, and this action will lift or free the top sheet from the pile *u* and allow free movement of same while being drawn off. The tilting table *v* is formed in 5 three sections, and the middle is shown as provided with a rubber or other pad 1, onto which the gripping-roller *t* grips the paper, so as to insure perfect action without slip.

Situate just under the tilting table is a shaft 10 2, carrying fingers 3, which fingers 3 have a motion on each side of the center section of the tilting table by cam from the main shaft for action upon a sheet or sheets of paper to replace them in the pile should by any means 15 more than one sheet be drawn up by the gripping-rollers. The axle of the fingers 3 is pivoted to the frame *c*. Said fingers are actuated by a rod 4, having a movement from cam 5, having a race for engaging the pin 6 of the 20 rod 4, which rod is slotted for encircling the main axle *r*, as shown.

Just at the back of the tilting table *v* is arranged a driving-roller 7, and above this roller 7 is situated a set of wheels 8, arranged on 25 knuckle-jointed or other levers 9, affixed to a rod 10, said rod 10 being actuated by a pin 11 on the cam 5 on the main shaft *r* to raise the wheels 8 to allow the paper to pass between them and the roller, the wheels 8 lowering to 30 grip the paper between them and the roller 7 for conduct to an inclined board 12, also having driven rollers 13, down which the sheet is carried to the ordinary stops of the printing-machine. Just before each sheet arrives at 35 the stops a cam 14 on the main shaft *r* fully operates through levers 15 16 or other mechanism a sliding bar 17, situate in the inclined table 12. This bar 17 carries a lever 18, weighted at one end to render it capable of 40 gripping the paper between its gripping-surface and the sliding bar 17, and when the bar 17 has been actuated a suitable stop 19 or other appliance on a rod 19^a, situate on the inclined table, will act upon the pin 18^a on the 45 weighted lever 18 and have lifted the gripping end from the sliding bar 17 to allow of the paper to pass underneath it, and on the return movement of the sliding bar 17 the stop 19 will free itself from the pin 18^a and allow 50 the gripping end of the lever 18 to drop and grip the paper, so that by the return movement of the sliding bar 17 the paper will be carried to the side stop 20 and placed in proper position for accurate side lay, and the gripping-surface will by reason of the resistance of side stop 20 slip over the paper, and just as the gripping-lever 18 has reached the end of its working stroke the stop 21 or other appliance, also on the rod 19^a on the inclined table, will act upon the pin 18^a and reverse or 55 raise the gripping-surface and release it from the sheet of paper ready for the grippers on the printing-cylinder to take it into the machine in the usual way. The weighted lever 60

18 or other device, together with the actuating devices 19 21 on the inclined table, is adjustable to suit sizes of sheets of paper to be printed.

When it is desired to feed two sheets at one time for printing, I employ two sets of rollers *t*, placed side by side, and the bar 17 is formed in two connected portions by suitable rods for a movement to and from each other, each portion being provided with a gripping and stop device to insure the necessary side lay. 75

When the sheet on the inclined table is in position for the cylinder-grippers, (not shown,) the inclined table 12 is at its lowermost point, and fingers 22, situate over the sheet, are dropped onto the sheet of paper to hold it 80 firmly in its proper position until the grippers are just about ready to grip the sheet, when the inclined table 12 is raised, and then the grippers take hold of the sheet and draw it through between the table 12 and the fingers 22, and when the sheet is entirely removed the table 12 lowers and the fingers raise, the next descending sheet falling into place to be adjusted for side lay, as with the previous sheet. The table is raised and lowered by any appliance on the printing-machine, and the fingers 22 are actuated from the lever 16 during the lowering movement of the table by a rod 23, connected also to a plate 24, over which an adjusting-screw 25 of 95 the finger-arm 26 rests, so that when the lever 16 is completely moved outward the plate 24 will be moved away for the adjustable screw 25, with the fingers, to fall; but when the table is raised sufficiently high the plate 24 will return to its normal position, ready for the finger-arm 26 and adjustable screw 25 to rest as before.

In connection with the paper-gripping roller 8 I provide a lever 27 or other appliance, so 105 that on each sheet being moved the rollers *t* will during the rotary movement of the knuckle-jointed bar *s* ride against the lever 27, and thereby be shifted a short distance to expose a fresh surface for the next sheet. 110

Having thus described the invention, what I claim is—

1. In feed mechanism for printing and like machines, a table adapted to receive a pile of paper, a shaft, a ratchet-wheel fixed to said shaft, a chain depending from the shaft and connected with the lower end of the table, a ratchet-wheel secured to said shaft, an oscillatory lever, a shaft fixedly carrying said lever, fingers fixed to said shaft for engaging the top sheet of a pile on said table, a cam for operating said oscillatory lever and thereby said shaft, a rod connected with one end of said lever and having a pawl for operating said ratchet-wheel in combination with a 120 spring-controlled knuckle-jointed lever, provided with a roller at its free end for engaging the paper upon said table and moving the 125

upper sheet of the pile therefrom, and means for actuating said lever.

2. In feed mechanism for printing and like machines, a table adapted to receive a pile of paper, a shaft, a ratchet-wheel fixed to said shaft, a chain depending from the shaft and connected with the lower end of the table, a ratchet-wheel secured to said shaft, an oscillatory lever, a shaft fixedly carrying said lever, fingers fixed to said shaft for engaging the top sheet of a pile on said table, a cam for operating said oscillatory lever and thereby said shaft, a rod connected with one end of said lever and having a pawl for operating said ratchet-wheel in combination with a spring-controlled knuckle-jointed lever, provided with a roller at its free end for engaging the paper upon said table and moving the upper sheet of the pile therefrom, means for actuating said lever, tilting fingers arranged to replace the lower of a plurality of sheets accidentally withdrawn from the pile, and means for actuating said fingers.

3. In feed mechanism for printing and like machines, a feed-table, a cam, a sliding bar ar-

ranged in coöperative relation with the feed-table and reciprocator by said cam, a weighted lever carried by the sliding bar and adapted with the said sliding bar to grip a sheet, and stops supported by said table for putting said weighted lever alternately into its effective and ineffective position.

4. In feed mechanism for printing and like machines, a plurality of sheet-engaging fingers, an oscillatory shaft to which said fingers are secured, an arm carried by said shaft and provided with an adjusting-screw, a pivoted plate adapted to engage said screw, a lever operatively connected with the pivoted plate, and means for intermittently actuating said lever whereby said pivoted plate is carried out of engagement with said screw.

In testimony whereof I have hereunto set my hand in presence of two subscribing witnesses.
